(57) **CLAIM**

The ornamental design for a forget-me-not overlaid infinity symbol ring, as shown and described.

DESCRIPTION

FIG. 1 is a perspective view;

FIG. 2 is a front elevation;

FIG. 3 is a top plan view;

FIG. 4 is a bottom plan view;

FIG. 5 is a partially-rotated left side elevation; and,

FIG. 6 is a partially-rotated right side elevation.

The broken line showing of environment in the drawings is for illustrative purposes only and forms no part of the claimed design.
